UNITED STATES PATENT OFFICE

JAMES P. McBRIDE, OF NEW YORK, N. Y., ASSIGNOR TO MUNKE JACK CORPORATION,
OF NEW YORK, N. Y., A CORPORATION OF DELAWARE

HYDRAULIC JACK

Application filed November 9, 1927. Serial No. 232,028.

My invention relates to improvements in hydraulic jacks, and my purpose, generally speaking, is to provide a hydraulic jack, all of the elements essential to the complete and continued operation of which are embodied in a unitary mechanism which is compact, light and therefore capable of being transported with facility from one location to another, and which is strong, durable and thoroughly reliable and efficient in operation.

More particularly it is my purpose to provide in a hydraulic jack, means whereby the liquid used in the operation of the jack is supplied to the pump element thereof under sufficient pressure to relieve the pump element of the necessity of any sucking action in its operation.

My inventive idea is capable of embodiment in different mechanical structures one of which is shown in the accompanying drawings. It is to be understood, however, that the structure shown is intended merely as a disclosure of the essential features and novel characteristics of my invention in one preferred form and that various changes and desirable additions may be made in and to the same within the spirit and scope of my invention as defined in the appended claims.

In the drawings, wherein like characters of reference denote corresponding parts in the different views:

Fig. 1 is a central vertical section through a hydraulic jack embodying the features of my invention;

Fig. 2, a vertical section taken approximately on the line 2—2 of Figure 1;

Fig. 3, a horizontal section on the line 3—3 of Fig. 2; and

Fig. 4, a perspective view of my improved valve.

Referring to the drawings in detail, 10 designates an elongated, hollow cylinder constituting what may be termed the housing of my improved jack, said cylinder including an outer, externally screw-threaded portion 12 and an inner portion 14 which latter, preferably, is of somewhat greater diameter than said outer portion and is equipped with a detachable base 16 for supporting the jack in upright position.

An elongated, hollow, cylindrical ram member 18, open at its inner end and closed at its outer end, is fitted neatly over the outer portion 12 of cylinder 10 and is adapted for longitudinal sliding movement with respect thereto, a safety nut 20 being threaded on said outer cylinder portion 12, inwardly of said ram member, to be run outward manually on said portion 12 into engagement with the inner end of the ram member, following projection of the latter, to prevent accidental collapse thereof with respect to the housing cylinder under the influence of a load on the jack if for any reason the means for projecting the ram member should fail to function properly.

A relatively long tube 22 is secured at its outer end to the outer, closed end of the ram member 18 and extends inwardly through a bushing 24 in the outer end of the portion 12 into cylinder 10, terminating, when the ram member is fully retracted with respect to the cylinder 10, as shown in Figure 1 of the drawings, a short distance from the inner end of the inner portion 14 of said cylinder 10.

Within the inner portion 14 of cylinder 10 is a piston 26 carried by the inner end of a rod 28 which extends into the tube 22 and is provided at its outer end with a head 30. A cap 32 is carried by the inner end of tube 22 and between this cap and the head 30 is arranged an expansion coil spring 34 which reacts from said cap through said rod to maintain a force on the piston 26 tending to move the same outward, whereby liquid 36 which is contained within the cylinder 10 is maintained under slight pressure.

Liquid is adapted to be supplied to the interior of cylinder in any suitable or desired manner, through tube 22 for example, for which purpose the outer end of said tube is provided with a removable plug 38.

Handles 40 are provided on the ram member 18 for facilitating handling of the jack.

Secured to the outer end of portion 12 of cylinder 10 is an annular cup gasket 42 one portion of which seals liquid tight against the inner face of ram member 18 and another portion of which seals liquid tight against the outer face of tube 22, whereby liquid forced

under pressure between said gasket and the outer end of the ram member will not leak into the cylinder 10 past the tube 22 or to the exterior of the jack past the adjacent sliding faces of the ram member and cylinder 10.

5 An extension 44 of cylinder 10 projects laterally from the inner portion 14 of said cylinder and has threadedly engaged therewith a pump cylinder 46 the inner end of which 10 opens into an inwardly tapering valve receiving recess 48 formed in said extension. A duct 50 provides communication between the inner end of recess 48 and the interior of cylinder 10 at a point in the latter preferably 15 in the vicinity of the junction of the inner and outer portions 12, 14 thereof, while another duct 52 leads from the recess 48 at a point spaced outwardly from the inner end thereof through the extension 44 and the wall 20 of the outer portion 12 of cylinder 10 and through the cup gasket 42 to the space between said cup gasket and the outer end of ram member 18. Said duct 52 has arranged 25 therein at any suitable point a check valve 54 opening outward and closing inward with respect to the recess 48.

The outer portion of the bore of pump cylinder 46 is of slightly smaller diameter than the inner portion thereof, and reciprocal in 30 the outer, smaller bore portion is a packed piston 56 equipped at its inner end with a cup gasket 58 secured thereto by an extension 60 of said piston which has detachable, screw-threaded connection therewith. Extension 35 60 preferably is of less diameter than the diameter of the inner portion of the bore of the pump cylinder to provide a space around said extension affording communication between the outer portion of the pump cylinder, within which piston 56 operates, and the recess 48. Said extension 60 moreover is tubular and open at its inner end and has slidably fitted therein the stem 62 of a tapered 40 valve 64 which is faced with leather or other 45 suitable material and is adapted to seat against the tapered wall of the recess 48 between the ducts 50, 52.

The stem 62 of valve 64 is split longitudinally as best shown in the detail view, Fig. 4, 50 to provide a pair of resilient tongues 66 adapted frictionally to engage the inner face of tubular extension 60 so that said valve is both movable with and with respect to said extension. As a consequence of this arrangement 55 when piston 56 and its extension 60 are moved outward valve 64 will be moved outward with the extension 60 away from its seat until its outer end strikes the inner end of pump cylinder 46 or any other suitable abutment, when 60 its outward movement will be arrested while the piston and its extension continue to move outward. In this way valve 64 is moved positively to open position directly by the piston. On the other hand, when piston 56 and its ex- 65 tension 60 are moved inward, valve 64 is

moved to its seat during a small initial amount of such inward movement, and being arrested by its seat, continued inward movement of the piston results merely in the extension 60 sliding over the stem 62, or, in other words, telescoping movement of the stem 62 with respect to the extension 60. Thus it is apparent that the arrangement described results also in the valve being moved positively directly by the pump piston to closed position. 70

The frictional engagement between the stem 62 of the valve and the extension 60 of the pump piston is sufficiently strong to maintain the valve closed against the pressure of the liquid 36 produced by the spring 34 and piston 26 whenever the valve is seated, spring 34 being relatively weak and only sufficiently strong to assure that the liquid contained in the cylinder 10 will be forced to the pump when valve 64 is open to relieve the pump of the necessity of sucking liquid from the cylinder 10 upon outward strokes of the piston 56.

Formed in the extension 44 is a recess 68, and branching off from the ducts 50, 52 are ducts 70, 72, respectively, which lead to said recess 68, a manually operable valve 74 of any suitable or preferred type being arranged within said recess and being movable either to a closed or an open position, in the former of which it cuts off communication between the ducts 70, 72 and in the latter of which it permits communication between said ducts. 90

Arranged between the cap 32 and the outer end of the portion 12 of cylinder 10, preferably around the tube 22, is an expansion coil spring 76 which constantly urges the ram member inwardly with respect to the said portion 12, so that when the valve 74 is opened the said ram member will be returned automatically to its normal position shown in Fig. 1 of the drawings. 100

A laterally and upwardly directed flange 78 on the pump cylinder 46 provides a seat which rotatably receives the lower end portion of a cylindrical casing 80 in one side of which is journaled a horizontal shaft 82 having fixed thereto an arm 84 operatively connected with the upper end of piston 56, whereby oscillation of said shaft reciprocates said piston, an actuating handle 86 being connected with said shaft for oscillating same. A ring 88 secured to the flange 78 and overlying a lateral flange 90 at the lower end of the casing 80 serves to establish a swivel connection between the pump cylinder and said casing, while a bolt 92 threaded in said casing with its inner end disposed in an annular groove 94 in the pump cylinder cooperates with said swivel connection to prevent outward movement of the casing and also provides means when tightened to lock the casing in any desired rotatably adjusted position with respect to the pump cylinder. When bolt 92 is loosened the casing 80 with 110 115 120 125 130 135

the handle 86 obviously may be rotated to dispose the handle in different positions with respect to the jack proper for most convenient operation. The casing 80 moreover is closed at its upper end and serves as a protective covering for the pump piston.

The operation of my improved jack is apparent and as follows:—Assuming the various parts to be in the respective positions shown in the drawings, that is, the ram member 18 retracted, valves 64 and 74 closed and the pump piston at its limit of inward movement, the jack is placed with its base against a suitable abutment and with the outer end 10 of the ram member against a part to be moved and handle 86 then is actuated to operate the pump to take liquid from the cylinder 10 and force it between the gasket 42 and the outer end of the ram member to project the latter. Upon outward movement of the piston 56, valve 64 is unseated and the recess 48 as well as the portion of the bore of the pump cylinder vacated by the piston 56 and its extension 60 becomes filled with liquid flowing 15 through duct 50 from the cylinder 10 under the combined influence of the spring 34 and piston 26 and the suction created by outward movement of the pump piston. Upon inward movement of the pump piston, 20 valve 64 is seated and since as a consequence the liquid trapped in the recess 48 and the bore of the pump cylinder cannot then return to the cylinder 10, valve 54 is forced open by the pressure on the liquid supplied 25 by the inwardly moving pump piston and the liquid then is caused to flow under pressure through the duct 52 to the space between the gasket 42 and the outer end of the ram member with the result that it reacts 30 from the outer end of the cylinder 10 to force the ram member outward. Upon repeated operations of the pump piston the ram member obviously is forced step-by-step outward and as the ram member is moved outward 35 the safety nut 20 should be threaded outward along the cylinder to form a stop to prevent inward movement of the ram member should the pump mechanism for any reason fail to function properly. When it is 40 desired to return the parts to normal position all that is necessary is to thread the nut inwardly on the cylinder 10 and open the valve 74 which permits the liquid to flow from between the gasket 42 and the outer 45 end of the ram member through the ducts 52, 52, 70 and 50 back into the cylinder 10.

It will be noted that since the tube 22 is carried by and moves with the ram member 18, piston 26 will be caused to follow up the 50 liquid 36 as it is depleted from the cylinder 10, so that the pressure of spring 34 remains at all times substantially constant.

I claim:

1. In a hydraulic jack, a hollow housing 55 adapted to contain a liquid, a ram member

carried by and projectible and retractible with respect to said housing, a pump arranged to take liquid from said housing and force it between the housing and said ram member to project the latter, and spring actuated means operable to force liquid from 70 said housing to said pump.

2. In a hydraulic jack, a hollow housing adapted to contain a liquid, the housing, a ram member carried by and projectible and retractible 75 with respect to said housing, a pump arranged to take liquid from said housing and force it between the housing and said ram member to project the latter, and means carried by and movable with said ram member to force liquid from said housing to said pump.

3. In a hydraulic jack, a hollow housing adapted to contain a liquid, a ram member carried by and projectible and retractible 85 with respect to said housing, a pump arranged to take liquid from said housing and force it between the housing and said ram member to project the latter, a piston within said housing movable to force liquid under 90 pressure from said housing to said pump, and spring means for so moving said piston.

4. In a hydraulic jack, a hollow housing adapted to contain a liquid, a ram member carried by and projectible and retractible 95 with respect to said housing, a pump arranged to take liquid from said housing and force it between the housing and said ram member to project the latter, a movable piston within said housing, and a yieldable support for said piston constantly urging the same in a direction to force liquid from the housing to the pump, a piston within said housing movable to force liquid under pressure from said housing to said pump, and a 100 yieldable connection between said piston and said ram member.

5. In a hydraulic jack, a hollow cylindrical housing adapted to contain a liquid, a hollow cylindrical ram member closed at its 110 outer end and slidably engaged over said housing, a pump arranged to take liquid from said housing and force it between the housing and said ram member to project the latter, a movable piston with said housing, and a yieldable connection between said piston and said ram member constantly urging the piston in a direction to force liquid from the housing to the pump, a piston within said housing, a yieldable connection between said 115 piston and said ram member, a pump, and means whereby said pump is operable to take liquid from said housing and force it between said abutment and the outer closed end of said ram member.

6. In a hydraulic jack, a hollow cylindrical housing adapted to contain a liquid, a hollow cylindrical ram member closed at its 120 outer end and slidably engaged over said housing, a tube extending inward from the 125

outer end of said ram member into said housing, an abutment on said tube, a rod within said tube having an abutment thereon, an expansion coil spring between the abutment on said tube and the abutment on said rod, said rod extending inwardly beyond the inner end of said tube and carrying a piston at its inner end slidably engaging said housing, a pump, and means providing communication between said pump and said cylinder and between said pump and the space between the outer end of the housing and the outer end of the ram member.

7. In a hydraulic jack, a housing, a projectible and retractable ram member mounted on the housing, liquid having an initial station within the housing on which the ram member is mounted, and a lifting station between the housing and ram member, a pump operable to force liquid to said lifting station to project the ram member, and a piston automatically operable against the liquid at the initial station during actuation of the pump to exert pressure on said liquid to force the same to the pump.

In testimony whereof I hereunto affix my signature.

JAMES P. McBRIDE.
